UNITED STATES PATENT OFFICE.

LEONIDAS G. WOOLLEY, OF KENTON, OHIO.

TELEPHONE AND FIRE-ALARM SIGNAL.

SPECIFICATION forming part of Letters Patent No. 695,260, dated March 11, 1902.

Application filed December 28, 1899. Serial No. 741,815. (No model.)

To all whom it may concern.

Be it known that I, LEONIDAS G. WOOLLEY, a citizen of the United States, residing at Kenton, in the county of Hardin and State of Ohio, have invented certain new and useful Improvements in Telephone and Fire-Alarm Signals; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to an improvement in telephone and fire-alarm signals; and it consists in the arrangement and combination of parts, which will be more fully described hereinafter.

20 The object of my invention is to have the telephone automatically turn in a fire-alarm to the central at the same time the occupants of the building are notified and to so construct the parts that if a person is too nervous

25 to operate the telephone he has only to break the pane of glass in a door of the telephone-box, when the alarm is sounded and transmitted to central.

In the accompanying drawings, Figure 1 is 30 a front elevation of my invention complete, showing the door of the telephone-box open and also showing the fire-alarm placed upon the same base as the telephone. Fig. 2 is a side elevation of the telephone-box alone containing the operating mechanism. Fig. 3 is 35 a vertical section through the box, taken to one side of its center, so as to show my operating mechanism. Fig. 4 is a detail view of a portion of the operating mechanism. Fig. 40 5 is a perspective of the vertically-moving frame M' and the casting T'. Figs. 6 and 7 are detail views of the generator-shaft and the parts connected thereto.

A represents the base, upon which the 45 swinging transmitter-arm B, the box C, containing the operating mechanism, and the fire-alarm D are mounted. The swinging transmitter B is mounted upon the vertical rod E and is adapted to be adjusted vertically upon this rod, so as to be adapted to the height of the person using it. In the box C is placed the usual magneto-electric machine

F for signaling, and its shaft G extends on through the magnetomachine and through the opposite side of the box, where it is connected to the spring K, placed in the drum H. This shaft does not extend continuously across, but is divided just inside of the box, and upon the two abutting ends of the shaft G are placed two disks I, one of which is provided with a ratchet a and the other with a pawl b. When an alarm is turned in to central, the shaft G is revolved by its handle in the usual manner, but it does not operate the spring; but when the spring causes the drum H to revolve the pawl b engages with the ratchet a and causes the shaft to revolve, so as to transmit a signal to the central. The drum in revolving, actuated by the spring K, placed inside of it, turns the shaft G in the same direction that it would be turned by hand when a person turns in a signal, and in causing the shaft to revolve the signal is automatically transmitted to the central. This drum H and spring K are never operated except in turning in a fire-alarm signal.

In the front lower portion of the box containing the operating mechanism is the usual lever L, which cuts in the transmitter and cuts out the generator, and hence need not be more fully described. Also in the front portion of the box is the electromagnet M, placed in the local thermostatic circuit and which when energized attracts the armature N, which carries a catch O for holding the door P closed. Also placed upon the door P is the ringing apparatus Q, of the ordinary construction. The lever L instead of projecting through the side of the box, so as to hang the transmitter R upon in the usual manner, has connected to it a rod S, which extends down through the bottom of the box and connects with the lever T, upon which the receiver is hung in the usual manner. The lever T is placed below the box instead of inside of it as a matter of convenience, because the drum H takes up the room upon the side of the box in such a manner as to make it desirable to drop the lever down, as here shown. Pivoted in the front portion of the box at one side is the triangular-shaped frame U, which is made in a single piece, so as to get its bearings a considerable distance apart, and thus prevent the bearings from

being strained when the frame U is brought into operation. This frame swings through a very small arc of a circle and has secured to it the rod V, which bears against the inside of the glass door for the purpose of pushing the door open, so that its end under the tension of the spring W can swing outwardly. The outer free end Z of the frame U projects through a slot X in the side of the box, as shown in Fig. 1, and catches over the projection A', secured to the side of the drum, and thereby prevents the drum from revolving until the door is either opened or the glass in it is broken. The instant the door is opened, which may be done by the short-circuiting of the thermostat system or by breaking the glass, this end Z is swung outward by the spring W, as shown in Fig. 3, sufficiently far to release the projection A' upon the side of the drum H, and then the spring K causes the drum to revolve, so as to turn in a fire-alarm to the central. In order to limit the distance the drum shall turn, the stationary stop B' is secured to the side of the box, and when the drum has made nearly a full revolution the projection A' strikes against the stop B'. Before another fire-alarm can be turned in it is necessary to wind up the drum and make the end Z of the frame U catch over the top of the projection A' on the drum, as shown in Fig. 2. Then by closing the door the pressure of the glass against the rod V will hold the frame U pressed inwardly against the tension of the spring W and the end Z over the top of the projection A'.

In order to make sure that a fire-alarm is turned in whenever the door is opened or the glass in it is broken, I pivot in the side of the box a short shaft C', which has upon its outer end a lever D', which extends upwardly either against or in close proximity to the side of the drum H, and upon this upper end is placed a blade-like extension E'. Upon the inner end of the shaft C' is an arm G', which bears against the extension H' on the frame U and upon the upper end of the lever D', and extending at right angles thereto is an arm I', which is secured to its outer end, and extending through the side of the box is a pin J', which pin moves in the slot K'. As soon as the door is opened or the glass broken the spring W starts the frame U to turn upon its pivot, so that its free end swings outward, and thus leaves the drum H free to revolve. When the drum has nearly completed its revolution, the projection A' strikes the blade-like extension E' and forces the lever D' backward the full length of the slot K'. The arm G' will push against the extension H', forcing the free end of the frame U outward. By this construction in case the spring W does not move the frame U sufficiently to release the alarm mechanism the fire-alarm will be turned in by direct positive action, the alarm being operated by the frame striking the lever G''.

Pivoted at L' in the top of the box at one

side, so that it bears directly against the side of the box, is a rod or frame M' and which is provided with the slots N' and O' and which has secured to it a block-like extension P', and to which extension is connected a spring S' for the purpose of moving the frame M' upward when it is left free to move. Through the slot N' passes a guiding-screw, and into the slot O' projects the end of the lever L, so that when the spring S' raises the frame M' the lever cuts in through the spring R' the local circuit for the transmitter in the usual manner and through the spring S'' the signaling apparatus. Although a spring is shown as bearing against the lower end of the frame M' in Fig. 3, this is not necessary. Also secured to the inner side of the box along the side of the frame M' is a casting T', which has a projection U' extending outwardly toward the door and to which the outer end of the spring W is fastened and also has attached to it a spring V', which bears against the armature N and normally holds the armature back until it is energized by the magnet to allow the door to open.

In case a fire-alarm is turned in when no one is around and the receiver is suspended from the lever T in the usual manner, it will be impossible for the alarm to be transmitted as long as this lever and the lever L are depressed, for the local transmitter and the battery are cut out. In order to instantly raise both of the levers L and T and to cut in both the battery and the transmitter, the end of the lever L is made to extend into the slot O' in the frame M', and then this frame is pushed laterally at its lower end by means of the pin J'. When the fire-alarm is turned in, the spring S' instantly raises the frame M' and by drawing upward upon the outer end of the lever L raises the lever T through the connection S, with the weight of the receiver R upon it. The pin J' bears against the block-like extension P', which serves to keep the frame M' depressed by catching under the stop A'' on the casting T'. When the fire-alarm is turned in, the outward movement of the lever D' causes the pin J' to strike against the block P' and swing the frame laterally, so that the block P' is moved from under the stop A'', and then the spring S' is free to raise the frame M' and through this frame the levers L and T. By this construction it will be seen that it is not necessary for a person to be present when the thermostat turns in the alarm, or when a person is too nervous to use the transmitter and signaling apparatus in the usual manner the alarm can nevertheless be sent in. To the two posts C'' are connected the telephone-circuits in the usual manner, and to the posts D'' is connected a thermostatic circuit, which also operates in the usual manner. The wires of the thermostatic circuit extend through the building in the usual manner and are connected to thermostats of any suitable construction in each room or wherever desired, and in case of a

fire they complete the circuit, and thus turn in the fire-alarm through the mechanism above described. One of the wires of the thermostatic circuit connects with the magnet which 5 operates the catch upon the door.

When the thermostat turns in an alarm, it opens the door of the box, and the gong is operated mechanically by the outward movement of the frame U, which operates the lever G', pivoted in the bottom of the box, and which trips the spring-actuated mechanism for sounding the gong. There is nothing new in this part of the construction, and hence these circuits are not shown in detail. The 10 magneto calls up the central station, and the operator there hears the gong ring. This thermostat is not necessary to the operation of the fire-alarm, for the mere breaking of the glass in the door would be sufficient to 15 turn in an alarm automatically, so that while this thermostatic circuit is a great additional protection and adds to the value of the invention accordingly it can be dispensed with where watchmen are always on duty. The 20 breaking of the glass in the door allows the frame U to move outwardly, and this operates the lever G' so as to sound the gong.

Having thus described my invention, I claim—

30 1. In a telephone and fire-alarm signal, a pivoted swinging frame, a spring connected thereto for causing the frame to swing outwardly when the door of the telephone-box is opened or the glass in the door is broken, 35 in combination with a spring-actuated drum, having a projection upon its periphery, the free end of said frame being in contact with the projection on the drum, the short shaft C' provided with a lever upon its outer end 40 which is operated by the turning of the drum, and an arm secured to its inner end for forcing the frame outwardly when the short shaft is caused to revolve, substantially as shown.

2. In a telephone and fire-alarm signal, the 45 shaft G made in two parts, the two disks, one of which carries a pawl and the other a ratchet, and which connect the two parts of the shaft together, the spring, the drum H secured to the shaft and provided with a projection, and a handle secured to the opposite end of the shaft for revolving it, combined 50 with a swinging frame, a spring for starting it to move outwardly when the door of the telephone-box is opened or the glass broken 55 therein, and a mechanism operated by the drum for forcing the swinging frame outwardly when the drum is caused to revolve, substantially as set forth.

3. In a telephone, a magneto-electric generator for sending in signals to the central, a 60 spring-actuated mechanism connected to the shaft of the generator, and which is adapted to operate the generator for automatically sending in a signal to central in case of fire, 65 and a swinging automatically-operated frame placed in the box and held pressed inwardly by the door of the telephone-box, and a me-

chanically-operated alarm which is operated by the outward movement of the swinging frame when the door is opened or the glass in 70 the door is broken, substantially as set forth.

4. In a telephone, a magneto-electric generator for sending signals to central, a spring-actuated mechanism connected to the shaft of the generator, and which will also operate 75 the generator to send in a signal in case of fire, and a pivoted spring-actuated frame which is held pressed inwardly by the door of the telephone, and which frame prevents the spring-actuated mechanism from operating until the 80 door of the telephone-box is opened, or the glass in the door is broken, and a rod or lever operated by the outwardly-moving frame, and a mechanically-operated alarm which is tripped or set off by said rod or lever when 85 the pivoted frame is moved outwardly, substantially as described.

5. In a telephone, a magneto-electric generator, a spring-actuated mechanism connected to the shaft of the generator, and which is 90 adapted to operate the generator when an alarm of fire is to be turned in, a pivoted automatically-operating frame in the box of the telephone, and which prevents the spring-actuated mechanism from operating, and which 95 frame is held pressed inwardly by the door of the telephone-box, and a mechanism operated by said spring-actuated mechanism for forcing the pivoted frame outwardly when the door of the telephone-box is opened, or the 100 glass in the door is broken, substantially as set forth.

6. In a telephone, a magneto-electric generator, a spring-actuated mechanism connected to the shaft of the generator and which is 105 also adapted to operate the generator when a fire-alarm is to be turned in, a pivoted automatically-acting frame pivoted in the telephone-box, and which serves to prevent the spring-actuated mechanism from acting when 110 an alarm of fire is not to be turned in, a mechanism operated by said spring-actuated mechanism for forcing the pivoted frame outward when the door of the telephone-box is opened, or the glass in the door is broken, and a mechanism 115 for raising the lever, upon which the receiver is hung, when an alarm of fire is turned in, and which mechanism for raising the receiver-lever is also operated by the said spring-actuated mechanism connected with 120 the generator, and a mechanically-operated alarm which is tripped or set off by said pivoted frame, substantially as shown.

7. In an apparatus for the purposes described, a magneto-electric generator, a 125 spring-actuated mechanism connected therewith, and adapted to operate the same when a signal or alarm is sent in, a receiver, a lever for sustaining the receiver, means for raising the lever, and a separate mechanism 130 within the box adapted to automatically operate an alarm or signal when the door of the box is opened or the glass is broken, and to set in motion the mechanism for raising the

receiver-holding lever as it automatically operates the alarm, all being arranged substantially as shown and described.

8. In a telephone and fire-alarm signal, the spring-actuated drum provided with a projection upon its side, the lever D' which is operated by the turning of the drum, and which lever is provided with a pin J', the frame M' placed in the box and provided with slots L', N' at opposite ends, and an extension P', a spring for raising the frame, and lever L which has its end project through the slot N', combined with the casting T' having a pro-

jection U' which extends outwardly toward the door, the spring W, the pivoted swinging frame to which the spring is secured, the electromagnet M and its armature and the spring V' secured to the casting, and which serves to operate the armature N in one direction, substantially as shown and described. 15 20

In testimony whereof I affix my signature in presence of two witnesses.
